OF ROCKFORD, ILLINOIS

SPRAY GUN

Application filed October 29, 1928. Serial No. 315,669.

This invention relates to a spray gun or air brush for spraying the usual variety of liquid or semi-liquid materials, such as paints, fillers, enamels, varnishes, shellacs, stains, etc.

Spray gun manufacturers have heretofore been compelled to make various models to suit the different individual preferences of workmen accustomed to handling their guns differently. A spray gun preferred by one workman because of certain characteristics would not meet with the approval of another workman, and vice versa. This naturally made it a difficult proposition to merchandise and stock these devices, and it has been generally recognized that there is a demand for a spray gun more adaptable to different individual preferences as well as more adaptable to different working conditions. It is the principal object of my invention to provide a spray gun which is practically universally adaptable by virtue of certain adjustable parts provided thereon. More specifically stated, the spray gun of my invention has swingable goose-necks for the paint and air hose connections mounted on opposite sides of the head and arranged to be turned on a transverse axis to any desired position to lead the hoses in from beneath or above the handle, whichever way suits the operator or is most convenient for operating under given conditions. This feature does away with the objections noted since the individual workman can fix the gun to suit himself.

Spray guns have also commonly been provided with a rotary air nozzle, the turning of which from one position to another brought into play diametrically opposed air jet openings to change from a round to a flat spray. The necessity for turning the nozzle was, however, objectionable for several reasons. the principal objections being that one was never sure, after having changed from a round to a flat spray, that exactly the same spray would be obtained upon returning to the round spray, the adjustment being usually disturbed, and it was also more or less bothersome to have to loosen the air nozzle to permit turning the same and after the

turning thereof to retighten the same. It is, therefore, still another important object of my invention to provide a rotary valve inside the air nozzle which is operable from the outside and without necessitating any tampering with the air nozzle whatever to change from a round to a flat spray, or vice versa. A special feature of this auxiliary valve lies in the fact that it is assembled within and forms a unitary part of the air nozzle and is, therefore, removable and replaceable with said nozzle, thus making it unnecessary to handle extra parts.

Still other features of my invention, such as the provision of an air restriction valve for cutting down the volume of air to the amount required, and the provision of a needle valve in connection with the color nozzle, which is so mounted that it may be turned in addition to being reciprocated, so as to permit grinding in of the color nozzle discharge orifice whenever desired, will be fully described in the following specification in which reference is made to the drawings, wherein—

Figure 1 is a side view of a spray gun made in accordance with my invention showing in full and dotted lines how the paint and air hoses are arranged to be led in from beneath or above the handle and how a paint cup may be mounted on the one goose-neck instead of having the paint hose connected thereto;

Fig. 2 is a horizontal section on the line 2—2 of Fig. 1;

Fig. 3 is a detail on the line 3—3 of Fig. 2;

Fig. 4 is a front view of the nozzle structure;

Fig. 5 is a longitudinal section on the line 5—5 of Fig. 4;

Fig. 6 is a transverse section on the broken line 6—6 of Fig. 5;

Fig. 7 is a similar view showing the jet openings closed by the auxiliary valve, and

Fig. 8 is a perspective view of the color nozzle on an enlarged scale.

The same reference numerals are applied to corresponding parts throughout the views.

The spray gun of my invention comprises a head 10 suitably cast integral with a barrel 100

11, the butt 12 of which has a handle 13 fastened thereto on the under side. The latter is suitably molded of a material such as bakelite for lightness and cheapness and has two 5 or more holes 14 provided in a wall closing the upper end thereof through which studs 15 projecting from the butt 12 are arranged to be extended, nuts 16 being threaded onto said studs with the aid of a socket wrench entered through the open lower end of the handle. A hook 17 is suitably cast integral with the barrel 11 for the purpose of hanging the gun onto any convenient projection, as for example, on the tank of the spraying outfit. A 15 nozzle structure, indicated generally by the reference numeral 18, the details of novelty of which will be presently described, is mounted on the head 10, its color nozzle 19 being in communication with a liquid chamber 20 in 20 said head and its air nozzle 21 being in communication with an air chamber 22 in said head. A needle valve 23 controls the discharge of the liquid or semi-liquid material from the color nozzle 19 in a manner present- 25 ly to appear, and another needle valve 24 controls the discharge of air from the air nozzle 21, both needle valves being operable, as will presently appear, by trigger 25. So much for a general understanding of the 30 spray gun of my invention.

Spray guns, as heretofore constructed, have had the hose connections for the paint, or other material to be sprayed, and air connected thereto in divers ways. Most manufacturers of spray guns made various models with different hose connections in order to be sure to suit the fancy of workmen having different preferences. It is an acknowledged fact that although some workmen will insist 35 upon having the hose connections for the gun led in from beneath the handle, others prefer and insist upon having the hose connections made from above the handle. The merchandising and stocking of these devices has, 40 therefore, been a difficult proposition. Moreover, a spray gun having hose connections made in one way might be suited to certain classes of work and not at all suited to other work. That is to say, spray guns having fixed 45 hose connections were not adaptable to different working conditions. The spray gun of my invention has been designed with a special view to avoiding the objections just referred to, and has two goose-necks 26 and 27 swivelled on the head 10 for adjustment on a transverse horizontal axis permitting the paint and air hoses 28 and 29 respectively to be led in from beneath or above the handle 13. The 50 goose-necks are shown in full lines downwardly directed with the hoses attached thereto leading in from beneath the handle. Many workmen prefer this arrangement. In dotted lines, however, the hoses are shown leading in from above the handle, and the 55 goose-necks are shown as rearwardly directed 60

for connection therewith. Workmen who prefer that arrangement can, therefore, adjust the gun to suit their convenience. Thus, one model takes the place of two or more. Aside, however, from this advantage, there is another advantage with this construction; namely, that the gun can be adjusted to suit any job which may be encountered. For example, in ceiling work, where it would be 70 awkward to use a gun having the hoses leading in from beneath the handle, the goose-necks can be swung to the dotted line position shown in Fig. 1 to have the hoses led in from behind or above the handle. On the other hand, in the case of floor work where it would be 75 unhandy to use a gun having the hoses leading in from above or behind the handle, the goose-necks can be swung to the full line position shown in Fig. 1 for handier operation. The gun is therefore practically 80 universally adaptable to working conditions. The goose-neck 26 is mounted on a hollow boss 30 on one side of the head 10, and the goose-neck 27 is mounted on another hollow 85 boss 31 on the opposite side of the head, the boss 30 having communication with the liquid chamber 20 and the boss 31 with the air chamber 22. The bosses are externally threaded to receive gland nuts 32 for clamping the 90 goose-necks by means of tapered glands 33 onto the ends of the bosses. The tapered glands afford liquid and air-tight joints for the respective goose-necks, in addition to affording swivel adjustment, it being understood 95 that the gland nuts are tightened when the goose-necks are adjusted to the proper position in order to insure tight joints and also in order to keep the hoses in proper position. Where it is desired to use a paint cup 100 such as that indicated in dotted lines at 34 in Fig. 1, suitable provision may be made for mounting the same directly on the goose-neck 26. The connection shown at 35 is one threading onto the goose-neck, but it will be 105 evident that any other suitable form of connection might be employed.

The nozzle structure 18 is shown to best advantage in Figs. 4 to 8. The color nozzle 19 constitutes the internal nozzle of said structure, and the air nozzle 21 the external nozzle. The former is threaded into the open end of the liquid chamber 20 and has a cylindrical bore in the threaded shank portion thereof and a tapered bore in the head portion terminating at the tip of the nozzle in a restricted discharge orifice 36 formed exactly concentric with the rest of the nozzle. The needle valve 23, above referred to, extends through the nozzle 19 and has the tapered end 37 thereof arranged to close the orifice 36. The color nozzle is enlarged and provided with facets at 38 for the application of a wrench in the threading of the nozzle into the chamber 20 in the head 10. The nozzle is 115 tapered and reduced in size just in front of 120 125 130

the faceted part, as shown at 39, and between this part and the reduced cylindrical tip portion 40 has a cylindrical pilot portion 41 made precisely concentric with the discharge 5 orifice 36 and tip 40 for a purpose which will presently appear. The portion 41 is fluted longitudinally, as shown at 42, to provide air passages. Telescoping with the pilot portion 41 of the color nozzle is a cylindrical 10 sleeve portion 43 of the air nozzle 21, which in turn is machined in truly concentric relation with the air discharge orifice 44. The close fit of the pilot portion 41 within the sleeve portion 43 results in the orifice 44 being held in absolutely true concentric relation 15 with the orifice 36. Now, the air nozzle 21, as shown in Fig. 2, is arranged to be supplied with air under pressure through the port 45 in the head 10 communicating with the air 20 chamber 22, whenever the needle valve 24 is opened, as will presently appear. A gland nut 46 threading onto the head 10 serves to clamp the air nozzle 21 onto the head by its marginal flange 47, making an air-tight joint. 25 Air is, therefore, supplied through the passages 42 circumferentially of the tip 40 of the color nozzle and hence annularly with respect to the orifice 36 of said nozzle to produce a uniform, finely divided spray by 30 atomization of the paint or other liquid or semi-liquid material issuing from the color nozzle. The absolutely concentric relation of the two nozzles, and hence of their discharge orifices, obtained by the telescoping of the 35 one nozzle on the other is, of course, essential to the production of the uniform, finely divided spray. This feature I first disclosed in my co-pending application, Serial No. 222,481 filed September 28, 1927, in which applica- 40 tion I also pointed out that the telescoping fit of the air nozzle on the color nozzle insures the concentric relation irrespective of any slight variation in the axial relationship of the two nozzles such as is bound to occur 45 in different spray guns, owing to the fact that it is practically impossible, especially in quantity production, to produce the parts without some slight variation in size of a few thousandths one way or another from specified dimensions. In the present case I have 50 further improved the nozzle structure by extending the tip 40 of the color nozzle 19 slightly beyond the orifice 44 of the air nozzle 21 and slotted, saw-toothed, or otherwise 55 notched the extremity thereof as indicated at 48, as for example, by filing the tip criss-cross with respect to the orifice 36 deep enough so that the base of each notch or slot is approximately in the plane of the end of 60 the air nozzle 21. I have found that this mutilation of the tip of the color nozzle, and, of course, other forms of mutilation might be found by experiment to give similar results, affords much better atomization with less air 65 than has heretofore been required. I at- tribute this improved result to the fact that the mutilation of the tip of the color nozzle affords a greater area for the spreading of the paint by capillary attraction on the tip of the color nozzle for contact with the air 70 discharged annularly about the same. Owing to the fact that this spray gun operates with less air than other guns, I provide a restriction valve on the spray gun which can be regulated to suit requirements. 75 This feature will now be described.

Referring to Fig. 2, the needle valve 24 extends through a packing bushing 49 threaded into the air chamber 22 from the rear, and also through packing material 50 and a packing plug 51 threaded behind the bushing 49, the bushing 49, packing 50 and plug 51 together serving to afford an air-tight joint, similar to the liquid-tight joint afforded for the needle valve 23 by the bushing 52, packing 53 and plug 54 in the rear of the liquid chamber 20. The needle valve 24 is squared for a portion of its length behind the pointed reduced end 55, as indicated at 80 56, for reception in a square hole in a valve plug 57 threading into the air chamber 22 in front of the bushing 49. The plug 57 has a smooth, slightly tapered forward end 58 which would be arranged to seat at 59 in the air chamber 22 if the plug 57 were threaded forward far enough in said chamber. Now, the needle valve 24 has a knurled head 60 on the rear end thereof permitting the same to be turned by hand for the purpose of adjusting the plug valve 57 to restrict the flow 85 of air into the air chamber 22 from the air supply hose 29. The needle valve 24, nevertheless, has freedom for reciprocation in the plug valve 57 for the opening and closing of the port 45. A cross-head 61 has a slot 62 in one end thereof for reception of the cross-head in an annular groove 63 formed in the needle valve 24 intermediate the ends thereof. The cross-head has the rounded nibs 64 of the trigger 25 engaging the front thereof for operation of the cross-head by finger pressure on the trigger. Movement of the cross-head is first communicated to the needle valve 24 directly by the cross-head 61 by reason of the connection just described. A 90 sleeve 65, fitting about the needle valve 24, is reciprocable in a cylindrical bore 66 provided in the butt 12, wherein a coiled compression spring 67 is disposed engaging at one end on an annular seat 68 at the rear end 95 of the bore 66 and at the other end on an annular shoulder 69 formed on the sleeve 65 tending normally to move the needle valve 24 forwardly so that its pointed end 55 closes the port 45 in the head 10. Obviously, there 100 is nothing in the operating connection of the trigger 25 with the needle valve 24 to interfere with the free turning of the needle valve 24 for adjustment of the restriction valve 57; the valve 57 can be adjusted even when 105

the needle valve 24 is held open by the trigger 25. Thus, the workman can adjust the valve while he observes the character of the spray produced and is, therefore, able to obtain the right sort of spray without any guess-work and with a minimum loss of time.

The needle valve 23, as also appears in Fig. 2, is provided with a knurled head 70 on the rear end thereof by means of which the same is arranged to be turned for the purpose of, from time to time, grinding in the discharge orifice 36 of the color nozzle to insure good operation of the spray gun. In the past, the needle valve controlling the discharge of the paint or other liquid was invariably held against turning or else was not accessible so that it could be turned, and if the paint or other liquid dried onto the walls of the color nozzle at the discharge orifice, there was no way of remedying the difficulty except by taking the gun apart, as for example, by removing the color nozzle. It is, therefore, quite an advantage to be able to clean the discharge orifice of the color nozzle by simply turning the needle valve therein to grind it clear of any obstruction. In order not, in the turning of the needle valve for the grinding operation, to change its timed relation to the needle valve 24 controlling the discharge of air, the same should be simply turned back and forth in the sleeve 71, in which the same is threaded. The sleeve is shown as having an enlargement of one end of the bore thereof, as at 72, internally threaded to receive the threaded enlarged end portion 73 of the needle valve. The sleeve is held against turning by a lug 78 on the cross-head 61 engaging in a slot 78' provided in the end of the sleeve. The sleeve is slidably received in the cylindrical bore 74 provided in the butt 12, and a coiled compression spring 75 fits in said bore about the sleeve engages at one end on a seat 76 provided at one end of the bore and at the other end engages an annular shoulder 77 provided on the sleeve 71. Thus, the needle valve 23 is normally held closed but is arranged to be operated by the cross-head 61 by pressure on the trigger 25. The clearance appearing in Fig. 2 between the cross-head 61 and the end of the sleeve 71 indicates to what extent the needle valve 24 is opened in advance of the needle valve 23 when the trigger 25 is pressed. When it is desired to change this timed relationship between the two needle valves, the needle valve 23 is turned by means of the head 70 one way or the other to advance or retard the operation of the needle valve 23 relative to the needle valve 24.

Referring now more particularly to Figs. 4 to 7, the air nozzle 21 has a pair of knobs 79 soldered or otherwise suitably secured in holes 80 at diametrically opposed points on said nozzle, said knobs having air jet open-

ings 81 communicating with the bores 82 thereof which open into the interior of the air nozzle 21. I have provided an auxiliary valve 83 of a rotary type within the nozzle 21 operable by a peg 84 projecting through an arcuate slot 85 provided in the wall of the air nozzle, the said valve being generally of frustoconical form to fit within the air nozzle, as shown in Figs. 5 to 7, and being held in place by a split ring 86 seated in an annular groove 87 provided therefor on the inside of the air nozzle 21. The auxiliary valve 83 is, therefore, a permanently assembled part of the air nozzle 21 and when the air nozzle is removed and replaced, there are no extra parts to be handled and possibly mislaid or lost. The valve 83 has the small end thereof cut to the two-segment cam shape shown most clearly at 88 in Figs. 6 and 7. Thus, two ports 89 are formed on the valve 83 arranged to register with the ports afforded by the inner ends of the bores 82 of the knobs 79 when the valve 83 is turned to the position shown in Fig. 6. With the valve in this limit position there is a full capacity discharge of air from the jet openings 81 and a flat spray is produced. The valve 83 may, however, be turned to intermediate positions where the discharge from the jet openings 81 is cut down to any desired amount to change the shape of the spray produced. When, however, the valve is shifted to the other limit position shown in Fig. 7, the jet openings 81 are entirely cut off from communication with the supply of air and a round spray is produced. It will be seen that an almost instantaneous change can be made from a round spray to a flat spray or vice versa, and that the change does not involve any tampering with the air nozzle and hence there is no danger of changing its operating characteristics; exactly the same spray will be obtained upon returning to the round spray as was obtained before the change from the round spray to the flat spray. In most spray guns the air nozzle had to be turned to change from a round to a flat spray and that usually meant throwing the gun out of adjustment; if the gun happened to be operating just right before changing from a round to a flat spray, there was little likelihood of the same spray being obtained upon returning to the round spray. Moreover, the turning of the nozzle necessarily involved the loosening and retightening thereof, which in itself was more or less bothersome. A workman operating with a spray gun embodying the present feature has, therefore, many advantages over one working with one of the unimproved spray guns; he loses no time in changing from the one kind of spray to the other, and is always sure that his gun will operate the same after a change as before.

It is believed the foregoing description conveys a clear understanding of the

- various novel features of my invention. It should be understood that while I have made reference in the foregoing description to various specific details of construction, 5 these are merely for the purposes of illustration, and the appended claims are, therefore, intended to cover all legitimate modifications and adaptations coming within the spirit and scope of the invention.
- 10 I claim:
1. In a spray gun, comprising a body providing relatively fixed head and handle portions, a nozzle structure on the head having liquid and air chambers side by side for the discharge of liquid and air under pressure, and valves side by side extending into said chambers and operable from the handle, a pair of hollow bosses formed on said body extending approximately on the same transverse axis laterally from opposite sides thereof in front of the handle and in communication respectively with the liquid and air chambers, one being arranged to serve as an air connection and the other as a liquid connection, a pair of goose-necks swiveled on said bosses and arranged to be turned on a transverse axis relative to the body and handle to direct the free ends thereof as desired, the same being adapted to have communication with conduits for supplying liquid and air under pressure, and devices carried on said bosses and arranged to be tightened to clamp the goose-necks in adjusted position. 25
  2. In a nozzle structure for a spray device, the combination of an internal nozzle having a reduced tip provided with a central discharge orifice and an enlarged external cylindrical bearing portion behind the tip concentric with the discharge orifice, and an external nozzle having a reduced tip providing a transverse front wall having a central discharge orifice arranged to be substantially concentric with the first mentioned orifice and having a cylindrical bore behind said front wall 45 concentric with the discharge orifice therein arranged snugly to receive and telescope upon the aforesaid cylindrical bearing portion of the internal nozzle whereby to insure exact concentric relation between the discharge orifices of the two nozzles, the tip of the internal nozzle extending through and substantially beyond the discharge orifice of the external nozzle, and having the end thereof notched outwardly with reference to the discharge orifice of said internal nozzle, the notches being of sufficient depth so that their bases are disposed in a plane substantially coincident with the end of the external nozzle substantially as herein shown and described. 55
  3. In a spray gun comprising a body providing head and handle portions, and a nozzle structure comprising an internal color nozzle having communication with a liquid passage in said head, and an external air nozzle having communication with an air passage in 60
  4. In a spray gun comprising a body providing head and handle portions, and a nozzle structure comprising an internal color nozzle having communication with a liquid passage in said head, and an external nozzle having communication with an air passage in said head, a trigger, an air valve arranged to be operated thereby, and a needle valve having the forward end thereof made conical and extending into the color nozzle and normally seated in the discharge orifice thereof, said needle valve being arranged to be reciprocated by the trigger and having a part threaded on the rear end thereof arranged to be engaged by said trigger for that purpose, the said part being arranged to be held against turning relative to the needle valve, and said needle valve having a head on the extremity thereof for turning the same in either direction whereby to adjust the needle valve in relation to the trigger and color nozzle, or for turning the same back and forth whereby to grind out the discharge orifice of the color nozzle. 95
  5. In a device as set forth in claim 4 wherein the said part has a spring acting against the same tending normally to seat the needle valve in the discharge orifice of the color nozzle, said part having a recess in the forward end thereof, a part operated by the trigger for operating said needle valve having a projection thereon received in said recess whereby to hold said part to permit threading of the needle valve therein in one direction or the other. 110
  6. In a spray gun or the like comprising a main body in the form of a barrel having a butt portion at one end thereof, a hollow handle formed in one piece open at the bottom and having a wall closing the top thereof, said wall having one or more openings provided therein, there being one or more studs projecting from the under side of the butt portion arranged to extend through said openings, and nuts threading on said studs inside the handle to fasten the handle to said butt portion. 120
  7. In a spray gun comprising a body providing head and handle portions, and a nozzle 125
  8. In a spray gun comprising a body providing head and handle portions, and a nozzle 130

structure comprising an internal color nozzle having communication with a liquid passage in said head, and an external air nozzle having communication with an air passage in said head, a needle valve for controlling the discharge orifice of the color nozzle, another needle valve controlling the discharge of air from the air passage to the air nozzle, a trigger arranged when operated to operate both needle valves, the last mentioned needle valve being free to turn relative to the trigger, and a valve plug threaded in the air passage arranged to restrict the flow of air through said passage as desired, said valve plug having such operative relation to the last mentioned needle valve whereby the same is arranged to be adjusted by turning of the needle valve but the needle valve is arranged to be reciprocated relative thereto in the operation of the trigger.

8. In a spray gun comprising a body providing head and handle portions, and a nozzle structure comprising an internal color nozzle having communication with a liquid passage in said head, and an external air nozzle having communication with an air passage in said head, a needle valve extending into the color nozzle and arranged to close the discharge orifice thereof, another needle valve disposed substantially in parallel relation therewith extending into the air passage and arranged to close the discharge end thereof, spring means normally holding said valves closed, a cross-head for operating both valves against the action of the spring means, and a trigger arranged when pressed to communicate movement to the cross-head, the first mentioned needle valve being arranged to be turned relative to the cross-head and having a head on the rear end thereof to facilitate turning the same by hand for the purpose of grinding out the discharge orifice of the color nozzle whenever desired.

9. In a spray gun comprising a body providing head and handle portions, and a nozzle structure comprising an internal color nozzle having communication with a liquid passage in said head, and an external air nozzle having communication with an air passage in said head, a needle valve extending into the color nozzle and arranged to close the discharge orifice thereof, another needle valve disposed substantially in parallel relation therewith extending into the air passage and arranged to close the discharge end thereof, spring means normally holding said valves closed, a cross-head for operating both valves against the action of the spring means, and a trigger arranged when pressed to communicate movement to the cross-head, the first mentioned needle valve being arranged to be turned relative to the cross-head, a head on the rear end of said needle valve facilitating the turning thereof by hand for the purpose described, a

part threadedly mounted on the needle valve behind the cross-head having the spring means acting against the same tending normally to hold the needle valve seated, the said part being arranged for engagement by the cross-head to unseat the valve and being held by the cross-head against turning with the needle valve, whereby to permit threading of the needle valve relative thereto to change the operative relation between the needle valve and the trigger at the cross-head.

10. In a spray gun comprising a body providing head and handle portions, and a nozzle structure comprising an internal color nozzle having communication with a liquid passage in said head, and an external air nozzle having communication with an air passage in said head, a needle valve extending into the color nozzle and arranged to close the discharge orifice thereof, another needle valve disposed substantially in parallel relation therewith extending into the air passage and arranged to close the discharge end thereof, spring means normally holding said valves closed, a cross-head for operating both valves against the action of the spring means, and a trigger arranged when pressed to communicate movement to the cross-head, the second needle valve being free to turn relative to the cross-head, a restriction valve for controlling the flow of air through the air passage, and means providing an operating connection between the restriction valve and the needle valve permitting free reciprocation of the needle valve relative to the restriction valve but permitting operation of the restriction valve by turning of the needle valve.

11. In a spray gun comprising a body providing head and handle portions, and a nozzle structure comprising an internal color nozzle having communication with a liquid passage in said head, and an external air nozzle having communication with an air passage in said head, a needle valve extending into the color nozzle and arranged to close the discharge orifice thereof, another needle valve disposed substantially in parallel relation therewith extending into the air passage and arranged to close the discharge end thereof, spring means normally holding said valves closed, a cross-head for operating both valves against the action of the spring means, and a trigger arranged when pressed to communicate movement to the cross-head, the second needle valve being free to turn relative to the cross-head, a head on the rear end of said needle valve facilitating the turning thereof by hand, said needle valve having a squared portion on the forward end thereof within the air passage, and a restriction valve plug slidably received on the squared portion of the needle valve and threadedly received in the air passage whereby the needle valve is free for reciprocation

relative to said plug but the plug is arranged to be adjusted by turning of the needle valve.

12. In a spray gun comprising a body having a head portion and a butt portion and provided with a handle, and a nozzle structure on the head portion, said nozzle structure including two substantially parallel needle valves extending rearwardly from the head portion in approximately the same horizontal plane toward the butt portion, a hollow boss on said butt portion providing two recesses therein one for each of said needle valves, spring means in said recesses for normally seating the valves, the needle valves being exposed between the head portion and said boss, means on the exposed portions of the needle valves providing shoulders for abutment by a trigger to unseat the valves, and a trigger arranged to engage said shoulders to unseat the valves.

13. A structure as set forth in claim 12 wherein the needle valve controlling the discharge of liquid from the nozzle structure has the rear end thereof projecting from said boss and provided with a knob on said end to permit manual operation of said valve independently of operation of the trigger.

14. A structure as set forth in claim 12 wherein the needle valve controlling the discharge of liquid from the nozzle structure has the rear end thereof projecting from said boss and provided with a knob on said end to permit manual operation of said valve independently of operation of the trigger, and wherein the means on the exposed portion of said valve comprises a member threaded on the valve for adjustment of the shoulder defined by said member toward and away from the trigger.

15. A structure as set forth in claim 12 wherein the needle valve controlling the discharge of liquid from the nozzle structure has the rear end thereof projecting from said boss and provided with a knob on said end to permit manual operation of said valve independently of operation of the trigger, and wherein the means on the exposed portion of said valve comprises a member threaded on the valve for adjustment of the shoulder defined by said member toward and away from the trigger, said member being held against turning and said valve being arranged to be turned by means of said knob to effect the adjustment.

16. A structure as set forth in claim 12 wherein the needle valve controlling the discharge of air from the nozzle structure has the rear end thereof projecting from said boss and provided with a knob on said end to permit manipulation of said valve independently of operation of the trigger.

17. A structure as set forth in claim 12 including a restriction valve in said head portion for controlling the flow of air through the nozzle structure, said valve being ar-

ranged to be adjusted by turning the same, the needle valve for controlling the discharge of air from the nozzle structure being extended through said restriction valve and arranged to serve in turning the same.

18. A structure as set forth in claim 12 including a single crosshead disposed for abutment with the shoulders on the exposed portions of the needle valves, the said crosshead being arranged to be engaged and moved by the trigger.

19. In a spray gun, an elongated body having a head portion at the front and a handle portion at the rear end in a fixed spaced relationship to one another, a nozzle structure on the body portion for the discharge of liquid and air under pressure, said body having liquid and air passages provided therein communicating with the nozzle structure, liquid and air conduits communicating with sources of liquid and air supply and disposed on opposite sides of the body in front of the handle portion, and means on opposite sides of the body between the head and handle portions for establishing communication for the liquid and air conduits with the liquid and air passages, said means being so constructed and disposed with relation to said handle portion to permit extension of the conduits from the spray gun in any one of several different directions with relation to the handle and always in balanced relation to said handle.

20. In a spray gun comprising a body having passages provided therein for conducting liquid and air to a head portion of the body, a nozzle structure on the head portion including an internal nozzle communicating with the liquid passage and having a substantially central discharge orifice, and an external nozzle communicating with the air passage and having a substantially central discharge orifice concentric with the first mentioned orifice, the external nozzle also having a pair of secondary air jet openings at substantially diametrically opposed points with reference to the central orifice and normally communicating with the air passage, said external nozzle being of tapered form internally, a rotary valve tapered externally to fit inside the external nozzle for rotation from a closed to an open position, or vice versa, to control communication between the secondary air jet openings and the air passage, the external nozzle being removable from the head portion to afford access to the internal nozzle and permit cleaning, means on the external nozzle behind the rotary valve to hold the same in place, whereby to seal the secondary air openings when the valve is in closed position and whereby also to permit removal of said valve with the external nozzle as a unit, and means on the rotary valve projecting through a slot provided in the wall of the external nozzle

to permit manual operation of said valve from outside the nozzle structure.

21. In a spray gun, the combination of an elongated body having a head portion at the front end and a handle portion at the rear end in a fixed spaced relationship to each other, a nozzle structure on the head portion for the discharge of liquid and air under pressure in the form of a spray, there being liquid and air passages provided in said body communicating with the nozzle structure, there being also laterally extending entry passages provided on said body on opposite sides thereof communicating one with the liquid passage and the other with the air passage, said entry passages being in a predetermined spaced relation to the handle portion behind the head portion, and a pair of flexible conduits attached to the opposite sides of the body in communication with the entry passages, the one having communication with a source of air under pressure and the other having communication with a source of liquid supply, the conduits being independent of one another but arranged to be extended together from the body in any one of several different directions with relation to the handle portion, the same being in any case in balanced relation to said handle.

22. In a spray gun, the combination of an elongated body having a head portion at the front end and a handle portion at the rear end in a fixed spaced relationship to each other, a nozzle structure on the head portion for the discharge of liquid and air under pressure in the form of a spray, there being liquid and air passages provided in said body communicating with the nozzle structure, there being also laterally extending entry passages provided on said body on opposite sides thereof communicating one with the liquid passage and the other with the air passage, said entry passages being in a predetermined spaced relation to the handle portion behind the head portion, a pair of rigid goose-necks of a certain form having angular inner ends extending toward each other from opposite sides of the body and registering with the aforesaid entry passages, the outer ends of said goose-necks being adapted one to have communication with a source of air supply under pressure and the other with a source of liquid supply, and means for connecting the inner ends of said goose-necks with the body to swivel with respect thereto to any one of several different positions, said goose-necks being normally extended in the same direction from the body so as to be in balanced relation to the handle.

23. A spray gun comprising an elongated body having a head portion at one end and a handle portion at the other in a predetermined relationship, a nozzle structure on

the head portion, liquid and air passages provided in the body communicating with the nozzle structure, and liquid and air connections for the spray gun communicating with the liquid and air passages and extending laterally from opposite sides of the gun in forwardly spaced relation to the handle.

In witness of the foregoing I affix my signature.

SWAN F. ANDERSON.
